UNITED STATES PATENT OFFICE.

WILSON F. SMITH, OF EAST LIVERPOOL, OHIO.

SOUND-AMPLIFIER.

1,370,375.

Specification of Letters Patent. Patented Mar. 1, 1921.

Application filed January 4, 1919. Serial No. 269,649.

To all whom it may concern:

Be it known that I, WILSON F. SMITH, a citizen of the United States of America, residing at East Liverpool, in the county of 5 Columbiana and State of Ohio, have invented new and useful Improvements in Sound-Amplifiers, of which the following is a specification.

The object of the invention is to provide 10 a sound amplifier as a means of confining and directing a resonating column of air, which shall be capable of concentrating and rendering sonorous the tones, simple and compound of a musical instrument or a 15 producing apparatus such as a phonograph, while preserving with integrity the relative values of the fundamental and overtones or harmonics and which shall not, through sympathetic vibration unduly emphasize 20 the latter, and particularly the dissonant harmonics which, while serving in their normal and subordinate values relative to the fundamental and consonant overtones to enrich the tone, produce a disagreeably 25 discordant impression upon the ear when they become disproportionately prominent.

To this end the invention consists in providing an amplifier of relatively non-resonant material, incapable of responding with 30 any perceptible degree of sympathy, either as a whole or in part to the relatively short and rapid vibrations incident to the overtones, and in providing the wall of the amplifier with a surface which while generally 35 smooth or regular is minutely broken, irregular or granular, so that as the sound waves impinge thereon the broader and longer vibrations of the fundamental and consonant overtones are subject to the concentrating 40 and amplifying effect of the shape of the device as a unit while the tendency is to disperse or merge the short sound waves of the dissonant overtones instead of directly reflecting them as when a glazed or polished 45 surface is provided for their contact.

In other words, the invention consists in providing a device of this class which shall eliminate or at least minimize both sympathetic vibration of the medium itself, such 50 as a horn or its equivalent, and the direct re-

flection of the shorter sound waves, which represent the dissonant overtones, and thus dispense with the collateral and undesirable sound effects which are incident to metallic, wooden, glass and porcelain amplifiers and 55 others which are not only resonant and subject to sympathetic nodal vibrations but are polished, varnished, planished, glazed or otherwise finished to provide sensitively reflective surfaces.

In carrying out the invention the sound wave concentrating and amplifying medium, which may be of the horn shape illustrated in the drawing is constructed of 60 baked clay.

The wall is preferably of uniform thickness throughout, with the bell 10 connected with the sound receiving terminal, or inlet 11 by a neck which may carry an integral 65 bracing web 12.

Also, the bell, as indicated may be of elliptical form, but modifications in shape may be resorted to without departing from the principle involved, and which is best exemplified in providing the device with a wall 70 of amorphous or non-crystalline structure, without grain or lamina, but of minutely granular material, such as clay, suitably shaped and baked and finished with an unglazed and unpolished inner surface which, 75 while generally smooth or regular in contour is minutely rough or granular as produced by the molding of the plastic clay, and which by reason of these characteristics is possessed of the properties herein before 80 specifically described.

The invention having been described, what is claimed as new and useful is:—

1. A sound amplifier having a wall of 85 baked clay.
2. A sound amplifier having a wall surface of unglazed baked clay.
3. A sound amplifier having a wall of 90 baked clay provided with an unglazed reflecting surface.
4. A sound amplifier having a wall provided with a granular surface.

In testimony whereof I affix my signature.

WILSON F. SMITH.
